UNITED STATES PATENT OFFICE.

GEORGE F. SLATER, OF WEST PALM BEACH, FLORIDA.

PORTABLE BUILDING.

Application filed September 2, 1926. Serial No. 133,267.

This invention relates to improvements in portable houses of that type in which previously constructed building units are assembled and secured together to form a structural whole. It particularly relates to a ceiling structure in which panels or slabs are mounted in a frame supported by the side walls of the house and it has for its object the utilization of this panel supporting frame to maintain the room partitions in their assembled relation to the exterior walls of the building.

The invention will be described in detail hereinafter, pointed out in the appended claims and illustrated by the accompanying drawings.

In the accompanying drawings, in which similar reference characters designate corresponding parts.

Figure 1 is a plan view, partly in section and parts broken away or removed, of a ceiling section embodying the invention.

Fig. 2 is a vertical sectional view on the line 2—2 of Fig. 1.

Fig. 3 is a similar view on the line 3—3 of Fig. 2, showing the under side of the ceiling section with all the panels in place.

Fig. 4 is a vertical section on the line 4—4 of Fig. 1.

Fig. 5 is a detail sectional view on the line 5—5 of Fig. 1, showing particularly the fastening device for holding the parts together.

Fig. 6 is an end view of the holding device.

Figures 7 and 8 are detail perspective views showing ends of the panel supporting members or moldings.

Fig. 9 is a detail perspective view of one of the ceiling panels.

Fig. 10 is a detail perspective view showing one of the ceiling beams.

Fig. 11 is a detail sectional view on the line 11—11 of Fig. 1, showing particularly one of the holding irons.

Fig. 12 is a detail view showing the interlocking joint between the moldings at a corner of the panel.

This ceiling structure is particularly designed for small dwellings constructed of portable sections that have been previously shaped and fitted so that the only work required in the erection is the positioning of the several parts in their assembled relation and securing them together. This system of building construction is particularly

adapted to small houses of one story in height, several rooms deep and but a single major room in width, the whole being covered by a gable roof. In the erection of such buildings the flooring is first laid upon a suitably prepared foundation, and upon the flooring side frames are erected and to which the exterior and interior walls are secured in the form of composite sheet material. Between the inner walls the cross partitions are mounted and the whole secured together. It is to such a structure that the ceiling of the present invention is applied. The drawings show the detail construction of the upper part of a major room—one extending entirely across the house—with the ceiling structure of the present invention embodied therein.

Referring to the drawings in detail, mounted on the top plates 20 of the opposite side frames of a major house section are the cross beams 21 which carry the ceiling panels. Each beam end extends part way across the adjacent plate and is secured thereto by the hook iron 22 (Figs. 1 and 11) the shank of which extends through the plate and the end of the hook engages the hole 23 in the end of the beam. The under side of the end of the beam is cut away, as at 24 (Fig. 10) so that the lower part of the beam abuts the inner wall 25 and serves to hold the latter in place against the inner edge of plate 20. As there are several of the beams 21 engaging the inner side walls, these walls are firmly held in place against the upper parts of the side frames by the cross beams. These interior walls are formed of sheet fibrous material 26 which are first cut to fit the inner side of the frame, but before the sheet is secured in place it is coated on its inner surface with a hard surface finish 27, such as waterproof plaster or other suitable material. As the hard finish is difficult to cut with tools, the fibrous sheet is first cut and fitted before the finish is applied.

In the opposite longitudinal faces of each cross beam 21 extend the grooves 28 in which are seated the molding strips 29 and 30 to carry the ceiling panels 31. As shown in Figs. 1-3, there are three beams 21 extending across the room section and they carry four ceiling panels 31 (only one of which is shown in place in Fig. 1), but the number of beams and panels may be varied to suit the size of the room. The three beams divide

the ceiling into two sections extending across the room and in each section are mounted two panels 31. These panels, which are formed of the same material as the interior side walls 25, are supported on the molding strips 29 and 30. A molding strip 29 extends across each end of the panel section abutting the adjacent interior side wall 25 and with its ends, which are cut away at 32 (Fig. 9) for the purpose of extending into the grooves 28 of the opposite beams 21. At intermediate parts of the cross beams, similar strips 29 extend across the sections to subdivide the latter. Extending along the inner sides of the cross beams are the molding strips 30, having longitudinal flanges 33, Fig. 8, extending into the grooves 28 between the ends of the strips 29. The mold strips seated in the cross beams mutually hold each other in place and serve to hold the strips 29 at the ends of the panel sections against the upper edges of the interior wall sheet 25 against the sides of the plates 20 of the side frames. At the angles where the mold strips abut, the strip 31 has a tongue 34 (Fig. 12) that overlaps the strip 29 that gives a finished appearance. When the strips 29 and 30 are in place, the panels 31 are placed on the strips between the cross beams and their weight holds them in place without further provision for the purpose. The transverse and longitudinal mold strips form a seat that is open on its upper side, clear of the inner faces of the opposite cross-beams and the adjacent wall section, so that the panel can be positioned in the seat from above. The foregoing construction not only provides a ceiling that is easily erected, but also one that will give the panel and beam effect desired for ornamental purposes.

In addition to supporting the ceiling panels, the cross beams 21 are also utilized in securing in place in the upper ends of the cross partitions. Each cross partition comprises a frame 35, to the opposite sides of which are secured the sheets 36 of coated fibrous material to form the walls of the adjacent rooms. Preferably, a partition is placed so that its side edges overlap the adjacent edges of contiguous wall sections, as shown in Fig. 1. The upper edge of each partition is clamped between the cross beams 21 of adjacent ceiling sections. The beams with the upper edge of the partition between them as shown in Fig. 5, are secured together by the three-pronged fastener 37 driven into the same. The wedge shape of the prongs driven into the adjacent member, serve to force the beams and partitions together. The under side of the fastener is wedge-shaped and serves to cut into the three connected members to hold them rigidly in place. A number of these clips are driven into different places, as required, to hold the

parts together. In Fig. 1 is shown an elongated pronged fastener 37' extending across two adjacent ceiling sections, its prongs being driven into the underlying cross beams 21. In this way the upper parts of the interior cross partitions are firmly clamped in place.

With the several parts so constructed and joined together, the house can be readily and easily erected and also easily taken apart without injury, should it be required.

What I claim is;

1. In a portable building, the combination with opposite wall sections, of cross-beams spaced apart and mounted on the wall sections with their ends secured thereto, said cross-beams having longitudinal grooves in their inner faces, mold strips seated in said grooves to form a seat open on its upper side clear of the inner faces of the cross-beams, and a ceiling panel introduced from above the cross-beams and resting on said seat.

2. In a portable building, the combination with opposite wall sections, of cross-beams spaced apart and mounted on the wall sections with their ends secured thereto, said cross-beams having longitudinal grooves in their inner faces, transverse mold strips extending between the cross-beams with their ends seated in the grooves of said cross-beams, longitudinal mold strips having flanges extending along the same and seated in the grooves of said cross-beams between the ends of said transverse mold strips, said transverse and longitudinal mold strips forming a seat open on its side clear of the inner faces of the cross-beams, and a ceiling panel introduced from above the cross-beams and seated on said seat formed by the mold strips.

3. In a portable building, the combination with opposite walls with each wall formed of contiguous sections, of a transverse partition extending between the opposite walls with the side edges of the partitions abutting the adjacent edges of contiguous wall sections, cross-beams extending between the walls on opposite sides of the partition, means for securing the ends of the cross-beams to the walls, and means for clamping together the partition and the cross-beams on opposite sides of the partition.

4. In a portable building, the combination with opposite walls with each wall having a plate extending along its upper edge and an inner face of sheet material extending along the inner side of said plate and cross-beams extending between said walls with their ends secured to the opposite wall plates, each of said cross-beams being cut away at its ends to drop between the opposite walls and to abut the sheet material to hold the latter against the sides of the wall plates.

In testimony whereof I affix my signature,
GEORGE F. SLATER.
